UNITED STATES PATENT OFFICE.

CYRIL GEORGE PULLIN, OF LONDON, ENGLAND.

SUPPLEMENTARY CARBURETOR FOR STARTING INTERNAL-COMBUSTION ENGINES.

1,424,320.

Specification of Letters Patent. Patented Aug. 1, 1922.

Application filed June 9, 1919. Serial No. 302,916.

(GRANTED UNDER THE PROVISIONS OF THE ACT OF MARCH 3, 1921, 41 STAT. L., 1313.)

To all whom it may concern:

Be it known that CYRIL GEORGE PULLIN, of 18 Ranelagh Avenue, Barnes, London, S. W. 13, a subject of the King of Great Britain and Ireland, whose post-office address is 18 Ranelagh Avenue, Barnes, London, S. W. 13, England, has invented certain new and useful Improvements in Supplementary Carburetors for Starting Internal-Combustion Engines (for which I have filed an application in England, June 7, 1918, Patent No. 156,272, dated January 13, 1921), of which the following is a specification.

This invention relates to improvements in supplementary carburetors for starting internal combustion engines, more particularly to carburetors in which the primary charge of petrol or other motive agent is caused to pass to the induction pipe or induction manifold of the engine through a carbureting chamber, or tube or through a tube or receptacle containing cotton wick, cotton waste or other surface vaporizing material, and has for its object to ensure a reliable supply of petrol or other fuel to the carburetor as required and to provide simple and effective means of control for regulating the supply of mixture or fuel and air therefrom to the induction pipe.

According to this invention the admission of the starting mixture of fuel and air to the induction pipe is controlled by a valve which also controls directly or indirectly the admission of the fuel to the carburetor, or vaporizer. The invention also includes means whereby the fuel supply to the carbureting or vaporizing chamber is regulated and maintained constant.

The invention is hereinafter described with reference to the accompanying drawings in which similar parts are indicated by the same reference characters throughout the different figures.

Figure 1 is a sectional elevation of a supplementary carburetor or starter constructed according to this invention.

Figure 2 is an elevation of the same viewed at right angles to the plane of section of Fig. 1.

Figure 3 is a horizontal section through the valve casing with the plug or valve removed.

Figs. 4 and 5 are transverse sections taken through different parts of the plug to illustrate passages therein.

As shown in Figures 1 to 5 a vaporizer

tube *a* containing cotton wick or other suitable material *b* is mounted on a plug valve casing or body *c* fitted with a taper plug *d* provided with an arm *e* which is connected to a control lever, but other operative connections may be employed. Between the wick or the like in the vaporizer tube and the valve casing a disc *f* of wire gauze or perforated sheet metal is interposed to prevent the wick from entering the vapour outlet or passage in the valve casing. The valve body *c* is formed with a screw-threaded boss or nipple *c'* for screwing into the induction pipe, with another nipple *c''* for the attachment of the fuel supply pipe, to which fuel is fed by gravity or pressure, and with a further nipple *c'''* from which a pipe *g* is led to a hollow plug *h* at the top of the vaporizer tube *a*. As shown pipe *g* is attached to the plug *h* and to the nipple *c'''* by unions *g'* and *g''*. Plug *h* is fitted with a needle valve *i* and communicates with the vaporizer tube *a* through an inlet orifice *h'* regulated or adjusted by the needle valve *i*. A cap *a'* fixed to the top of the vaporizer tube *a* is formed with a central circular recess *a''* into which the hollow plug *h*, carrying the needle valve, is screwed, the bottom of the recess being perforated or provided with a passage as shown to admit the fuel to the vaporizer tube *a*.

Around the top of the vaporizer tube, apertures *a'''* are made for the admission of air, such apertures being suitably protected against the ingress of water and grit by a depending flange or cowl *a''* provided for that purpose on the cap *a'*. A fuel passage *d'* is formed in the plug valve *d* between fuel passages *j*, *j'* in the body *c* and is adapted to put the nipple *c''* and the fuel supply pipe connected therewith in communication with the nipple *c'''* and pipe *g*, whilst a compound passage *d''* *d'''* is formed in the plug between mixture or vapour passages *k* *k'* in the body *c* for putting the vaporizer tube *a* in communication with the induction pipe through the nipple *c'*. A gauze covered extra air inlet *c''* is also controlled by the compound passage *d''* *d'''* by which it can be put in communication with the induction pipe through the passage *k'* after the mixture has been cut off.

In operation the plug valve *d* is turned from the closed position to first put the fuel supply pipe in communication with the pipe *g* leading to the top of vaporizer tube from

whence the fuel passes under the control of the needle valve *i* into the wick or other material in the tube *a*.

A further movement of the plug valve 5 opens the passages *k* and *k'* for admitting mixture to the induction pipe and the final movement of the plug valve cuts off the fuel passage and the mixture passage and leaves only the air inlet *c*⁴ open to the induction 10 pipe, for the supply of extra air if required. The air from the inlet *c*⁴ passes to the induction pipe through the delivery passage *k'* which previously delivered mixture or vapour to the induction pipe.

15 I claim:

1. A supplementary carburetor or starter for internal combustion engines, comprising a valve having a body attachable directly to the intake manifold of an engine 20 and a plug member rotatable in the body, and a carbureting or vaporizing chamber mounted on the body of said valve, said vaporizing chamber being provided with a fuel supply passage and a mixture outlet 25 passage, the rotatable plug of the valve being provided with means operable by rotary movement of its plug to open and close both the fuel supply passage and the mixture outlet passage.

30 2. The structure recited in claim 1, said vaporizing chamber having an air inlet therein, said valve having an air inlet therein, the last mentioned air inlet being operable by the plug of the valve by turning said 35 plug to a position for closing the fuel supply passage and the fluid mixture outlet.

3. The structure recited in claim 1, the carburetor being provided with a cap on its top, said cap having therein a fuel inlet, 40 and a needle valve mounted to operate in said fuel inlet and co-act therewith to regulate the flow of fuel into the vaporizing chamber.

4. In a supplementary carburetor or 45 starter for internal combustion engines, the combination of a valve casing attachable to the intake manifold of an engine, a carbureting or vaporizing chamber mounted on said valve casing and provided with an 50 air inlet and a vapor outlet, absorbent material in said vaporizing chamber between said air inlet and vapor outlet, said vaporizing chamber being provided with a passage to conduct liquid fuel to said absorbent

material, and a valve in position to coact 55 with the valve casing for controlling the flow of vapor through said vapor outlet, means also being provided for controlling the supply of liquid fuel through said valve, said valve casing and valve having openings 60 therethrough to register and permit flow of liquid fuel through the valve and casing when the valve is in position to close the vapor outlet, and means to conduct liquid fuel from the said registering openings to 65 the fuel inlet passage of the vaporizing chamber.

5. The structure defined by claim 4, said valve casing having therein a vapor passage in open communication with said vapor outlet of the vaporizing chamber, said valve casing also having therein a delivery passage that delivers vapor to the induction pipe, said valve casing also having therein an air inlet, said valve being operable to 70 selectively establish communication between said vapor passage and delivery passage and between the last said air inlet passage and delivery passage.

6. In a supplementary carburetor or 80 starter for internal combustion engines, the combination of a main valve casing attachable to the intake manifold of an engine, a carbureting or vaporizing chamber mounted in said valve casing and provided with air 85 inlets near its top, said chamber being provided with a cover including a central depending cavity or liquid fuel receptacle, said receptacle having passages in position to direct liquid fuel outward into currents of 90 air from said air inlets, a needle valve casing secured to said cover and having its outlet in communication with said liquid fuel receptacle, a needle valve in the needle valve casing to control the flow of liquid 95 fuel into said receptacle, a main controlling valve in the main valve casing, and means to conduct liquid fuel from said main valve casing to said needle valve casing, said main valve being operable in the main valve cas- 100 ing to control the flow of liquid fuel into said needle valve casing and also to control the flow of vapor from said vaporizing chamber.

In testimony whereof he has affixed his 105 signature.

CYRIL GEORGE PULLIN.
